UNITED STATES PATENT OFFICE

PAUL F. BOYD, OF CHICAGO, ILLINOIS

RETOUCHING DEVICE

Application filed December 29, 1928. Serial No. 329,147.

The present invention is directed to improvements in retouching devices.

The primary object of the invention is to provide a device of this character so constructed that photographic negatives can be accurately and expeditiously retouched.

Another object of the invention is to provide a retouching device so constructed that the density of the negative portion can be increased upon inscribing thereon minute circles in lieu of the dots and lines now commonly used.

Another object of the invention is to provide a device of this character so constructed that the circles inscribed may vary in diameter.

Another object of the invention is to provide novel means for mounting the lead in order that the same can wobble during operation without the danger of breaking the same.

Another object of the invention is to provide a device of this character which is simple in construction, efficient in operation, and one which can be manufactured at a small cost.

With these and other objects in view, this invention resides in the novel features of construction, formation, combination and arrangement of parts to be hereinafter more fully described, claimed and illustrated in the accompanying drawing, in which:—

Figure 1 is a longitudinal sectional view through the device.

Figure 2 is a sectional view on line 2—2 of Figure 1.

Figure 3 is a sectional view on line 3—3 of Figure 1.

Figure 4 is a fragmentary, longitudinal sectional view through the device, showing the auxiliary unit attached thereto.

Figure 5 is a sectional view on line 5—5 of Figure 4.

Figure 6 is a sectional view through the lid supporting sleeve.

Referring to the drawings, 1 designates a tubular casing having end closures 2 and 3, and a partition 4, said partition being disposed near the closure 2 to provide a chamber 5.

Mounted in the chamber 5 are pinions 6, preferably four in number, said pinions having shafts 7 which have their respective ends journaled in the closure 2 and partition 4. An endless toothed belt 8 is trained around the pinions 6 in order that they will rotate in unison. One of the shafts 7 is provided with a socket member 9, the purpose of which will appear later.

To the forward ends of the shaft 7 are suitably fixed disks 10, said disks having arcuate sweeps formed upon their peripheries for successively engaging the marking lead 12 to impart thereto a gyratory movement. The disk 10 which is driven positively is provided with a head 13, the purpose of which will be later explained.

A tube 14 is provided and has its forward end fitted in the partition 4, while its outer end is fitted in the closure 3 and it is in this tube that the lead 12 is confined. In order to hold the lead yieldably supported a rubber sleeve 15 is provided and in which the outer end of the lead is engaged. The sleeve is confined in a metal casing 16 in order to permit the same to slide within the tube without undue friction.

Having its forward end fitted in the socket member 9 is a driving shaft 17, the outer end of which is connected with a flexible driving connection 18 driven by a motor 19. Any other suitable driving means may be provided if found more desirable.

Obviously when the shaft 17 is driving the associated pinion 6 the remaining pinions will be rotated through the instrumentality of the belt 8, thus imparting rotary movement to the sweeps 11 to cause the same to successively engage the lead 12 to impart thereto a gyratory movement in order that the lead

will inscribe circles upon the negative during the retouching process. The sweeps 11 are of such size as to inscribe comparatively small circles, and in order that slightly larger 5 circles may be inscribed I provide a readily detachable auxiliary unit for accomplishing this. This unit comprises a cylindrical head 19' having mounted therein partitions 20 and 21 defining a chamber 22 therebetween. 10 Mounted in the chamber are pinions 23 the shafts 24 thereof being journaled in the partitions, as clearly shown in Figure 4 of the drawings.

The shafts 24 have fixed to their outer ends 15 disks 25 which are slightly greater in diameter than the disks 10, and like said disks have peripheral sweeps 26.

One of the disks 25 has a socket 27 formed therein for detachably receiving the head 20 13 in order that when the head 19' is fitted upon the casing 1, as shown in Figure 4, the pinions 23 will be driven simultaneously through the medium of the belt 28. The head 19' is provided with a conical portion 29 25 in which is provided an opening 30 to accommodate the lead 12.

It will be obvious that when the auxiliary unit is placed upon the casing 1 that the sweeps 26 of the disks 25 will cause the lead 30 to inscribe comparatively small circles. Thus it will be seen that the device can be used for inscribing circles varying in size.

The speed of the motor 19 may be regulated by a friction brake, or in any manner desired.

Owing to the presence of the rubber sleeve 15 the lead will be normally centralized within the tube 14 and can wobble when subjected to the action of the respective sweeps.

When the device is used without the auxiliary unit I provide a casing 31 adapted to be fitted upon the casing 1, as shown in Figure 1, the casing 31 having an opening 32 formed therein to accommodate the lead.

Since the sweeps 26 successively engage the lead the action thereon is similar to that of the sweeps 11 carried by the disks 10.

From the foregoing, it is thought that the construction, operation and many advantages of the herein described invention will be apparent to those skilled in the art, without further description, and it will be understood that various changes in the size, shape, and proportion and minor details of construction may be resorted to without departing from the spirit or sacrificing any of the advantages of the invention.

What is claimed is:—

1. A device of the class described, comprising a casing, a plurality of pinions mounted in the casing, a belt for simultaneously rotating the pinions, disks connected with the pinions and having sweeps upon their peripheries, a lead mounted in the casing and extended between the disks and successively en-

gaged by the sweeps during rotation of the pinions.

2. A device of the class described, comprising a casing having a plurality of pinions mounted therein, a belt trained around the pinions, means for positively driving one of the pinions, said pinions having disks fixed thereto, said disks having arcuate sweeps carried thereby, a lead engaged in the casing and extended between the disks, said sweeps being adapted to successively engage the lead to impart movement thereto, and means for yieldably supporting the lead. 70

3. A device of the class described, comprising a casing, a tube mounted in the casing, a driving shaft mounted in the casing, a plurality of pinions mounted in the casing, means for simultaneously rotating the pinions when the driving shaft is rotated, said pinions having disks connected therewith and having peripheral sweeps, a lead engaged in the tube adapted to be successively engaged by the sweeps during rotation of the disks, and means for yieldably supporting the lead within the tube. 80

4. A device of the class described, comprising a casing having a plurality of pinions mounted therein, disks connected with the pinions and having sweeps carried thereby, a head carried by one of the disks an auxiliary unit having pinions therein provided with disks having sweeps carried thereby, means for interlocking the disks of the unit with said head, and means for driving the first named disks, and thus the disks of the auxiliary unit, 95 and a lead mounted in the casing and subjected to the action of the sweeps of the pinions of said unit. 100

5. A device of the class described, comprising a casing, a tube mounted in the casing, a resilient sleeve mounted in the tube, a lead having its outer end engaged in the sleeve, a plurality of pinions mounted in the casing and having disks connected therewith, said disks having sweeps carried thereby for successively engaging the lead during rotation of the disks. 105

6. A device of the class described, comprising a casing, a lead mounted in the casing, a plurality of pinions having shafts journaled in the casing, a socket member carried by one of the shafts, disks carried by the shafts, a driving shaft engaged with the socket member for imparting rotary movement to the associated shaft, a belt trained around the pinions and sweeps carried by the disks for successively engaging the lead when rotary motion is imparted to the pinions. 110

7. A device of the class described, comprising a casing having a plurality of pinions mounted therein, means for simultaneously driving the pinion, disks connected with the pinions, an auxiliary unit including a plurality of pinions having disks connected there- 120

with, said disks having sweeps carried thereby, means for interlocking a disk of said unit with one of the first named disks for simultaneously driving the pinions of the unit, and a lead engaged with the casing and successively engaged by said sweeps.

5 8. A device of the class described comprising a casing, a plurality of pinions associated therewith, means for simultaneously rotating the pinions, sweeps driven by the pinions, and a marking device in the casing adapted to be successively engaged by the sweeps during rotation of the pinions.

In testimony whereof I affix my signature.
